RECORD ALBUM

Folger Adam, Joliet, Ill., assignor to Thomas A.
Banning, Jr., Chicago, Ill.

Application September 3, 1946, Serial No. 694,554

2 Claims. (Cl. 206—62)

1

The present invention has to do with improvements in record albums, and the like. These albums are widely used for holding and storing phonograph records in orderly fashion, and frequently according to various groupings of such records, such as groupings of the records of selected symphonies, concertos, and other recordings. Heretofore it has generally been the custom to provide these albums with pockets or separators within or between which the several records are placed, so that when the album is closed each record is carried within its individual pocket or space. When thus stored these individual records stand on edge when the album is set into a cabinet or other suitable place; and when each record is contained in its own pocket it is evident that the weight of such record is carried primarily by the bottom of such pocket. These pockets are generally made of paper of suitable weight, but nevertheless the weight of the contained record is generally such that such a relatively flimsy pocket is incapable of holding the weight of the record for more than a relatively short time, if at all, without the record becoming lowered to a position such that its weight eventually rests directly on its lower edge portion, and is sustained directly by the shelf or other place of storage. In this process it is evident that if the pocket is originally designed to sustain the record's weight, such weight must be taken by the bottom portion of the paper or other material from which the pocket is made; and in due course of time the result is generally that the back portion of the pocket which is connected to the back of the album becomes distorted sufficiently to allow the record to press the pocket down until the weight of the record itself is carried directly by the shelf or other supporting medium. This result almost invariably follows a relatively short interval of storage of the records in the album, notwithstanding that the pockets themselves may be made of relatively stiff and strong paper stock.

It is furthermore evident that when the records are sustained directly by the pockets which in turn are hinged to the back of the album, the entire and combined weight of all the records, possibly as many as a dozen records, must be carried by this album back. This weight is transmitted to the pockets at a position approximately half-way across the width of the album from the back of the album; and with records of standard sizes of ten and twelve inches diameter, it is evident that the weight of the records is transmitted to the back through a turning moment of five or

2

six inches. This fact, combined with the very substantial weight of the records themselves, means that, if the records are to be sustained entirely by the record album and free of direct support by engagement of the lower edge portions of the records with the shelf, the back of the album will be subjected to a very large bending and distorting moment due to the weight of the contained records. Since the back of the album is itself hinged to the album covers by relatively flimsy hinged connections, it is further evident that such bending moment will be transmitted to the covers through such flimsy hinges, with the result that the album itself will be distorted and its appearance will soon be correspondingly impaired. These results must necessarily follow if the weights of the records are to be continuously carried by the individual pockets, and without said pockets sagging to allow the edges of the records to find direct support by the surface of the shelf or other supporting element.

It is therefore evident that either or both of the foregoing undesirable results must follow from the continued use of such record albums as have heretofore been extensively known and used; either the backs of the albums will become distorted and the hinges between the backs and the album covers will become distorted or eventually torn; or else the individual pockets themselves will become distorted and eventually torn or broken; or both of these undesirable results will be found to occur.

There have in the past been devised various schemes to mount and support the individual records on a stud or the like extending across the thickness of the album, on which stud the several records are mounted by stringing their center holes on such stud. Generally these studs have been supported by one of the album covers in permanent fashion, and frequently such stud has been engaged by the other cover when the album is in closed condition, so that thereby the stud is given support at both ends during the interval of album closure. However, when the album is opened it is evident that the weight of the records strung on the stud must be sustained and supported solely by such stud, if the records are to be sustained free of the shelf or other supporting medium. Therefore, at such times the back cover of the album is necessarily subjected to a large twisting moment, since the weight of the records lies in a plane forward (or backward) of the plane of the cover itself by an amount equal to substantially one half of the combined thickness of the records then in place

on the stud. This twisting moment is a serious force which will soon act to distort the hinge by which the back cover of the album is connected to the back of the album itself, and increase of such distortion will only cease when the records have descended sufficiently to allow them to attain direct support by the shelf itself.

The principal object of the present invention is to provide a record album of the stud type, that is, the type in which the records are strung onto a stud secured to one of the covers, but which album is provided with means to directly support and carry such stud as a portion of the back of the album itself, and generally without the interposition of any hinged connection between the so-supported stud and the back of the album. In other words, the albums herein disclosed are generally provided with a non-articulated or non-hinged back portion (or front portion) which constitutes and is really a portion of the back of the album itself; and the stud is then secured directly to this so non-articulated or non-hinged cover element, so that all the forces of weight placed on such stud by the records strung thereon are transmitted directly to the rest of the album which is non-articulated or non-hinged to such cover and stud. Since the back of the album extends horizontally a distance at least equal to the combined thickness of the supported records, and since the said stud really constitutes a portion of, or is rigidly connected to such back of the album, it is further evident that this arrangement serves to ensure provision of a base for the album, which base is of sufficient horizontal dimension transversely of the album, to carry the full weight of the sustained records, within the projected area of such base. Thus there is no overturning tendency due to the weight of the records, providing, of course that the album is placed on a substantially horizontal surface, such as a shelf.

Another way of stating this feature of the present invention is as follows:

I provide a stud which is primarily intended to act as a support on which the records contained in the album are hung. This stud is in turn rigidly connected to and supported by a cover or an element connected to and comprising in effect a portion of such cover, which element is of sufficient rigidity to effectively support the stud and the weight of the records strung thereon, the connection between the stud and such cover or cover element being of sufficient strength to enable the stud to carry its load of records solely by attachment of the stud at one end to such cover or cover element. By this means the weight of the contained records is supported solely by said stud, which stud is in turn supported solely at its end which is connected to the cover or to the cover element. I then provide for such cover or cover element a suitable stand or base support whereby said cover or cover element is effectively supported in vertical position, thus giving effective support to hold the stud in horizontal position at the distance above the shelf or table on which the stand or base is placed, so that the contained records are supported with their edges completely above such shelf or table or other element. Such support for the cover or cover element may be in the form of a back for the album proper; said back having a dimension transversely of the album (thickness) sufficient to provide the required base area for the album as a whole

so that said album will stand on the horizontal shelf or table without other support. In this case such back of the album may constitute a rigid portion of the rigid cover or cover element, so that these two parts (back and cover or cover element) constitute an unarticulated combination of L-shape cross-section; or said back portion and said rigid cover or cover element may be hinged together with a definite hinged connection of such construction that no appreciable bending or distortion may take place as between the back section and the cover or cover element at the position of such hinged connection, so that the required base is always provided between the back section and the lower edge of the cover or cover element, even though the back section and the cover element are not in exact right-angular position with respect to each other. Such a hinged connection is to be distinctly differentiated from such a flimsy hinged connection as is provided by the cloth hinges generally provided between the back sections and the cover elements of such record albums as heretofore constructed.

When the back section and the cover or cover element are rigidly connected together (without such hinged connection) it is evident that a very simple and inexpensive type of construction may be used, since the cover or cover element may be in the form of a plate of sheet metal or very stiff plastic or other material, either integral with the rigid back section, or rigidly connected thereto, either by screwing, welding, riveting, cementing, or by a gripping or other rigid connection, or otherwise. It is also evident that since the objective of providing a rigid support for the stud requires only that such support extend downwardly from the stud to the shelf or table or other surface by which the album is supported, such rigid plate or other element need not extend above the height of the stud; and that portion of the cover to which the stud is connected, or to which the cover element is connected, above such height may be formed of relatively light, and inexpensive, and even of flexible material, or other material suitable for the construction of such covers.

The rigid cover or cover element to which the stud is connected, and by which the stud is solely supported, may find direct support by the shelf or table on which the album is supported, so that said rigid cover or cover element constitutes a point of support for the album and its contents. Such support thus effected by the rigid cover or cover element may be in the form of edge contact thereof with the shelf or table, or said cover or cover element itself may be provided with a transversely extending or right-angular extension at its lower edge which transverse extension will in such case constitute a base which will effectively support the album and its contents on the shelf or table. In such case such extension may be made of sufficient transverse dimension to provide such effective support as is needed. Such transverse extension may furthermore extend the full length of the rigid cover or cover section, or may extend only a portion of such length. In this latter case such transverse extension is preferably formed at or near that portion of the rigid cover or cover section which lies directly beneath the stud position, so that the required transverse support will be effectively provided. In this case, too, the rigidly connected or non-deflecting hinged back portion will constitute one of a two or

three point support for the vertical rigid cover or cover section.

If desired a suitable form of lock or latch may be provided for connecting the other cover section to the rigid cover section or element, to thereby secure both covers in closed position, the stud being of such length that these covers may be brought into such fully closed position relative to each other.

Frequently it will be desirable to provide means on or in connection with the free end of the stud to retain the records in place on such stud, and irrespective of the closing of the two covers together. I have therefore herein disclosed several forms of such means to retain the records in place on the stud, as will be hereinafter shown. Such means may be completely supported by and constitute solely a portion of the stud, or such means may be carried by and constitute a portion of the cover which does not carry the stud. In this latter case, too, such means may also constitute means to lock the two covers together in the sense that the non-stud carrying cover may thereby be locked or connected to the free end of the stud which stud is itself rigidly connected to the other cover or cover element.

Other objects and uses of the invention will appear from a detailed description of the same, which consists in the features of construction and combinations of parts hereinafter described and claimed.

In the drawings:

Figure 1 shows a perspective view of a record album embodying features of my present invention, and it shows by dotted lines one form of rigid cover or section to which the record supporting stud is rigidly connected, and the rigid cover or cover section being rigidly connected to the back section, and there being provided a latch to connect the two covers together if desired;

Figure 2 shows a plan view corresponding to Figure 1;

Figure 3 shows a perspective view of the rigid cover section and the rigid back section to which said cover section is non-hingedly connected, said rigid cover section being provided with a rigidly connected stud, and Figure 3 is on enlarged scale as compared to Figures 1 and 2; the elements shown in Figure 3 constituting an assembly section;

Figure 4 shows an enlarged fragmentary view of the rigid connection between the rigid cover section and the rigid back section; the rigid connection shown in Figure 4 including a series of triangular lugs stamped from the body of the sheet metal from which the cover section itself is formed, and said lugs being pressed into the body of the back section, or being moulded in said body if desired; and the rigid cover section being also cemented or otherwise rigidly connected to the rigid back section, if desired;

Figure 5 shows a fragmentary horizontal section taken on the line 5—5 of Figure 4, looking in the direction of the arrows;

Figure 6 shows a perspective view of one form of the rigid stud which is rigidly connected to the rigid cover section; the stud shown in this figure being provided with an eccentrically pivoted end element which is of size to permit the records to be set over said element when said element is turned into surface alignment with the body of the stud, and said eccentrically pivoted element naturally dropping down into interfering position after the records have been set onto the stud to

thereby retain the records on the stud without other assistance;

Figure 7 shows a fragmentary horizontal section through a stud of the form shown in Figure 6, and through the rigid cover section to which said stud is rigidly connected, the front cover being also shown adjacent to the end of the stud, being in cover closed position; and this figure also shows a number of records strung onto the

10 stud and supported thereby;

Figure 8 shows a perspective view of a modified form of the rigid cover and stud assembly, in which the rigid cover plate or cover element to which the stud is rigidly connected, being provided with a bottom or base pedestal which may find direct support on the surface of the shelf or table on which the album is supported; this figure also being on enlarged scale as compared to Figures 1 and 2;

Figure 9 shows a fragmentary horizontal section similar to that of Figure 7, but it shows a modified form of stud and modified form of front cover element, as compared to the construction shown in Figures 6 and 7, this modification consisting in the provision of a socket in the end of the stud, and the provision of a companion or male element on the other cover section, so that when the two cover sections are closed together such male element will enter into the socket of the end of the stud to retain the records in place on the stud by co-operation between the two covers themselves when said covers are closed together;

Figure 10 shows another modified form of stud on still further enlarged scale as compared to Figures 6, 7 and 9, the stud construction shown in Figure 10 including a slot or like opening formed in the end portion of the stud together with a spring clip set into said slot and riveted or otherwise secured in place therein, the free ends of said clip being suitably formed to provide abrupt surfaces which will spring into record retaining positions when the clip is allowed to extend under its own spring action to thus retain the records in place on the stud;

Figure 11 shows still another modified form of stud construction, together with a modified form of companion element formed or placed on the other cover of the album; this arrangement including a suitable groove or recess formed in the surface of the end portion of the stud, and a companion spring clip secured to the companion cover, so that when the covers are closed together this spring clip will spring over and engage with the groove or recess of the stud and thus secure the two covers together and also to retain the records in place on the stud;

Figure 12 shows still another modified form of rigid cover or cover element, and stud rigidly connected thereto, said cover or cover element being shown as hinged to the rigid back section by a hinged connection of such form that it is non-deflecting and of such construction that the rigid cover section is retained in definite relation to the rigid back section so that the cover and back sections together will provide a definite base to support the album on a shelf or table or other supporting surface; and

Figure 13 shows still another modified form of construction embodying my present invention, wherein the stud extends in both directions from the rigid stud-supporting plate, so that records may be strung on both projections of said stud.

Referring first to Figures 1 and 2, the record album herein disclosed is provided with the two

cover elements, 20 and 21, of size appropriate to accommodate the records intended to be contained in such album, generally either ten or twelve inch in diameter. This album also includes the back section 22 to which both of the covers are connected. The cover element 20 also includes the stud 23 which projects towards the cover element 21, and on which stud the records are intended to be strung by setting their central openings over such stud in the well understood manner. This stud is of such length as is required to accommodate the intended number of records to be accommodated in the album; and likewise the back section 22 is made of corresponding width so that the two covers may be brought into parallelism (closed condition) to bring the inner surface of the front cover close to or against the free end of the stud, and to close the album with the records in place on the stud.

The lower edge portion of the cover element 20 is carried down to such point that said lower edge, together with the lower end of the back section 22, may constitute a base support for the album and its record contents. Thus the stud is placed at an elevation above the lower edge of the cover element 20 at least as great as the radius of the contained records, and in fact, at a distance above said lower edge somewhat greater than such radius so as to ensure that the records strung on the stud will be supported solely by the stud and without edge contact of said records with the shelf or table on which the album is placed. Evidently under these conditions the full weight of all the contained records on the stud must be sustained solely by such stud; and furthermore, since such stud is generally supported solely by its connection to the cover element 20 it follows that such connection, and also the cover element 20, itself, and the connection of said cover element to the back section 22, must be such as to enable all these parts to effectively receive and sustain the relatively large forces which are thus imposed due to the weight of the supported records, sometimes as many as ten or twelve records.

Since it is desirable to form the cover element 20 proper of relatively light material, in order to reduce the weight of the album, and also is desirable to use relatively inexpensive material, such as paper stock or cardboard, or the like in its manufacture, it is at once seen that such a cover body is not of sufficient strength in and of itself to effectively support the stud without bending or distortion of such cover element sufficiently to allow the records to sag until they find direct contact with and support by the surface on which the album is placed. Such sagging also distorts the cover itself, and produces an unsightly appearance, as well as soon causing the cover to become torn and damaged otherwise. It is a prime feature of my present invention that I have provided a very stiff or a rigid support constituting a portion at least of one of the covers of the album, and to which the record supporting stud is rigidly connected at right angles to the plane of such cover element, together with a very stiff or rigid back section to which said stud support is itself connected in such manner that no distortion can occur as between said back section and said stud support. In the arrangement shown in Figures 1 and 2, and elsewhere in the drawings, this stud support comprises the stiff plate 24, preferably of sheet metal of sufficiently thick gage to afford the required stiffness as

10 between the point of stud connection to said plate and the edge portion 25 where said plate is connected to the back section 22. In the arrangement of Figures 1 and 2, as well as Figures 3, 4, 5 and 8, this plate 24 is rigidly and unarticulatedly connected to the back section 22, so that both the plate 24 and the back section cannot yield with respect to each other about any axis of yield. They are thus constrained to retain their right-angular relationship with respect to each other at all times, and any force which would be sufficient to effect a material deflection of the stud against the position of the back section would be much greater than any force to which the stud might be possibly subjected merely by reason of the placement of the records normally in place on such stud.

The back section 22 may be formed of wood, or may be of metal, or may conveniently be formed of plastic material of suitable stiffness and strength to meet the needs of the case. Or, if desired, both the stiff plate and this back section 22 may be made integral with respect to each other. Thus, they might be formed integrally of plastic or of very light metal, such as magnesium alloy, or aluminium alloy or the like. The stud may either be riveted or screwed or otherwise attached to the plate 24, as by welding, or in some cases this stud may be formed integral with the said plate, as by suitably forming a plastic body. In any case, however, the requirement of stiffness sufficient to carry the load of the supported records is a prime consideration.

25 In the arrangement shown in Figures 1, 2, 3, 4, and 5 the stiff plate 24 is provided with a number of triangular shaped projections 26 which are formed at right angles to the plane of such stiff plate; and these projections are shown as being forced into the body of the wood back section 22 to bring the surface of the plate 24 into facial contact with the edge of the back section; and preferably cement or other adhesive is also provided to connect the surface of the plate to the back section, in addition to the provision afforded by such triangular projections. Thus the plate 24 is very strongly connected to the back section 22, so that the stud 23 is, in turn, also afforded very stiff and unyielding support from the back section. Thus the support of said stud is effected directly from the stiff back section, and does not depend on the body of the cover element itself.

55 Said cover element is formed by the paper stock or other light material sheet or sheets 27 and 28 (see Figures 7 and 9), which conveniently embrace the stiff sheet support 24 between them to provide a neat and finished appearance for the cover element; but it is evident that these finishing sheets, which in fact constitute the body of those portions of the cover which extend beyond the confines of the stiff sheet 24, do not afford any portion of the support for the record carrying stud, and are completely supplemental to said stud supporting sheet 24. In fact, as far as the actual supporting of the stud itself is concerned, these sheets 27 and 28 might be eliminated.

Now it is evident from examination of Figure 3 and others, that even without the presence of the finishing sheets 27 and 28 the stiff plate 24 is given adequate support on the shelf or table, because the lower edge portion of the said sheet together with the lower end of the back section 22 provide a supporting base hav-

ing sufficiently large dimensions at right angles to each other to ensure upright stability of the device (composed of the plate 24 and the back section 22), even when the stud is fully occupied by records strung thereon. Then, due to the stiffness of the plate 24 and the unyielding nature of the connection between said plate and the back section 22, and the strong connection of the stud to the plate 24, it is evident that the records will be fully supported at all times by hanging on the stud, and without any contact of their lower edge portions with the supporting surface on which the device is placed.

In Figure 8 I have shown a modified form of the stiff plate 24 (designated as 24^a). In this case the said plate is itself provided at its lower edge with the right-angular extension 29 which may be of a horizontal dimension at least as great as the transverse dimension (thickness) of the album. This projection 29 is preferably formed directly beneath the location of the stud 23 so that thus there is afforded a full base for supporting the weight of the records by direct transmission of such weight from the stud downwardly to this base extension 29, and without the need of first transferring any portion of such weight to the back section 22. Of course when such transverse extension is provided in combination with the rigid connection to the back section 22, the said back section affords further transverse stability to the device, and also affords a material extension of the dimension of the rigid base lengthwise of the album.

The rigid connection of the stud to the stiff plate 24 (or 24^a) may be effected in any suitable manner, as by a riveting connection shown in Figures 9 and 7, at the points 30 and 31, respectively. In various of the other figures the stud itself is shown as provided with an end portion 32 of reduced size which is set through a suitable hole of the stiff plate and then secured by an upsetting operation in well understood manner.

The cover element 21 may be any convenient construction since it does not have to perform any mechanical or load supporting function, other than that due to its own weight. Conveniently such cover element 21 is formed from sheets or laminations of paper stock in the usual manner, and to the desired thickness and finish, but without the need of making special provision for stiffness as far as the presence of the records contained in the album is concerned.

Furthermore, the cover element 21 is preferably hinged to the back section 22 along the edge 33 as shown in Figure 1, such hinging being effected in convenient manner, as by the strip of strong flexible material 34 cemented to the edge portion of the surface of the cover 21 and to the surface of the back section 22. It is seen in Figure 1 that this strip is shown as being carried over the edge portion of the hinged cover element so as to effect connection thereto, but that said strip does not extend over that portion of the other cover element 20 which lies to the right of the back section 22, since in Figure 1 said back cover element is rigidly connected to the cover section 22, and is therefore unyielding with respect thereto.

Now it is evident that as far as the provision of a supporting base for the stiff plate which carries the stud is concerned, such base may be either a combination of the said stiff plate and the back section 22, or may be comprised solely of the lower edge portion of such stiff plate, as in

Figure 8, or may comprise both such lower portion of said plate and the back section 22 as shown in Figure 8 or in Figure 3. It is also evident that as far as this rigidity of support is concerned it is not necessary that the back section 22 and the said stiff plate lie directly at right angles to each other, provided that they do have substantially such right-angular relation when it is desired to stand the album on the shelf or table in self supporting condition, and provided that when in such other position of angularity these elements are so connected together that they cannot yield about any axis other than that line on which their planes intersect, and that they be of suitably stiff material to ensure proper support for the stud in horizontal position while carrying its load of records. Accordingly I have shown still another modified form of my improved albums in Figure 12. In that figure the stiff plate 24^b is shown as being hinged to the back section 22 by the vertical hinge 35 extending substantially the full height of the stiff plate 24^b so as to provide a very great degree of rigidity about a horizontal axis. This hinge is to be definitely differentiated from any form of hinge composed of cloth or other yieldable material or material of such flimsy nature as to be unable to afford the vertical stiffness required to ensure that the stud shall be so supported at all times that it will be retained in horizontal position, even when fully loaded with records of large size. In other words, in this modified arrangement of Figure 12 this hinge is of itself of such construction and strength that it is able to afford definite hinging action as between the stiff stud supporting plate 24^b and the stiff back section 22, so that even when the plate 24^b is not at right angles to the back section 22 no deflection of the plate can occur, other than a definite and controlled hinging action along the line of the hinge, and so that during such hinging action the stud is itself held strongly at right angles to the plane of the plate 24^b so that the records strung on such stud will still be sustained solely by hanging on the stud, and not by any direct edge support of such records on the surface of the shelf or table or other surface. It is also noted that this hinging construction is also shown in Figure 12 in conjunction with the provision of the lower edge pedestal portion 29^b similar to the pedestal 29 shown in Figure 8.

In the constructions shown in Figures 8 and 12, wherein the stiff plate 24^a or 24^b, as the case may be, is provided at its lower edge portion with the right-angular extension 29 or 29^b, it is seen that such extension, considered in conjunction with the stud 23 constitutes a U-shaped member, the lower leg of which constitutes a base to find support directly on the supporting surface, the upper leg of such U-shaped member comprising the stud, and the connecting portion of such U-shaped member comprising the connection between these parts. It is seen that with this arrangement the stud is very strongly held in horizontal position, the load is transferred directly from such stud to the supporting surface; and the stud will not sag or bend from its intended horizontal position, the vertical connecting element being of sufficient stiffness to prevent such action. With this arrangement the other (generally front) cover serves, in connection with the back section, primarily as an enclosing element, to give protection to the records thus supported on the stud, and, on occasion, to retain said records thus in place on the stud.

I have also provided means to retain the records so strung on the stud from becoming disengaged therefrom. Such means I shall now describe:

In the form of Figures 1 and 2 I have provided the catch or hasp 35 generally secured to the cover element 20 and of size to extend over and be snapped or otherwise connected to the edge portion of the cover element 21 to thereby hold the covers in closed position in well understood manner. The stud itself is then made of size to extend close to or into contact with the inside surface of the cover element 21 so that when the covers are thus locked together by such hasp the records are also retained on the stud, and are prevented from becoming disengaged from the stud as long as the album is so locked in closed condition.

In the scheme shown in Figures 6 and 7 I have provided the small plate 36 at the end of the stud, such plate being pivotally connected to the end of the stud by the small pin 37. This pin 37 is eccentrically placed so that when the small plate 36 is released it will naturally fall into such a position as that shown in Figure 6 wherein it extends below the cylindrical confines of the stud (extended), thus preventing the records from becoming released from the stud; but the arrangement is such that by rotating this small plate through substantially one-half turn it will be brought into registry with the cylindrical surface of the stud, so that thereupon the records may be released or placed on the stud as desired. The gravitational effect of this eccentric pivoting will be found to effectively retain the small plate in its locking position after said plate has been released and turned at least part way around towards its locking position.

In the modified arrangement shown in Figure 10 I have provided the inwardly extending slot 38 in the end portion of the stud, together with the inwardly extending socket 39 communicating with said slotted portion; and within this slotted and socketed opening I place the U-shaped spring element 40, of spring wire or narrow spring leaf. The connecting or inner end portion 41 is riveted or otherwise secured to the floor of the socket, and the biasing of the U-shaped element is such that its arms naturally spring out into contact with the axially extending walls of the socket, as shown in Figure 10 wherein said spring element is in its normally spread condition. The free ends of this spring element are formed with the outwardly extending abruptly formed portions 43, terminating in the slanting forward extensions 44 which finally terminate within the confines of the slotted portion when the spring arms are fully released or expanded into the position shown in Figure 10. As thus expanded the center hole of a record may be slipped over the end portion of the stud and over the slanting portions 44, thereby compressing the arms of the spring element momentarily towards each other; and as the surface of the record passes the abrupt portions 44 the spring arms will snap outwardly thus locking the record in place on the stud; but such record may thereafter be readily released from the stud by compressing such slanting portions together sufficiently.

In the modified arrangement shown in Figure 11 the stud itself is provided with an encircling groove 45, or with a pair of oppositely placed recesses; and the cover element 21 is provided with a spring clip element 46 having the spring

arms 47 terminating in the inwardly extending teeth 48 which will snap into such groove or into the oppositely and properly placed recesses, to thereby lock the cover element 21 to the stud, 5 and to thereby also lock the records on the stud as long as the album is in closed condition.

In the further modification shown in Figure 9 the stud itself is provided with the inwardly extending socket 49; and a small stud 50 is secured 10 to the cover element 21, either directly or by means of the thin plate 51 secured to or comprising a portion of the cover element 21. The stud 50 is so positioned on the cover element 21 that when the album is closed said stud 50 will 15 telescope into the socket 49 of the stud 23, thus locking the records in place on the stud as long as the album remains in closed condition. Preferably such arrangements as those shown in Figures 9 and 11 for retaining the records in place on the studs should be used in connection with means to lock the album covers in closed condition, such as the hasp shown in Figure 1, or other suitable album locking means may be used in place of such hasp.

25 In the embodiment of features of my present invention shown in Figure 13, I have provided the rigid stud supporting plate 24^c located centrally of the back element 22^a, so that said back element extends to both sides or faces of the 30 plate. The connection between the plate 24^c and the back element 22^a may be made in any convenient manner; but in the scheme shown in Figure 13 the back element is slotted to receive the edge portion of the plate 24^c, said edge portion 35 being inserted into such slot, and retained therein. Such retention may be ensured by the tightness of the fit of the plate in the slot; but preferably also additional retention is provided by cementing the edge of the plate in the slot, 40 and/or by use of transversely extending rivets, screws, pins, or other retaining elements.

The record supporting stud 23^a extends to both sides of the plate 24^c, the extensions at both sides conveniently being of equal amounts. The central portion of this stud may be rigidly connected to the plate in any convenient manner, as by welding or the like. The extension of this stud at each side of the plate should be approximately the same distance as the extension of the back 50 element beyond the face of the plate at that side of the plate. Preferably also the plate 24^c is provided at its lower edge with lateral extensions 52 at one side, and 53 at the other side, these extensions providing a base or pedestal support for the rigid plate. These extensions it will be noted, are located beneath the stud extension, so that the loads of records carried by these stud extensions will be transferred directly to this pedestal support. It will be understood that these stud 55 projections at the two sides of the plate may be of equal or different amounts, but generally they will be of equal amount. Thus the record storage capacity of such an album may be double that of an album of conventional form, or an album having the stud projection at only one side of the plate.

It will be understood that suitable covers may be hinged or otherwise connected to the edges of the back element, so that when said covers are swung into closed position the records at both sides of the album are given proper protection. I have not specifically illustrated such covers in Figure 13, as a matter of convenience in illustration; but it will be understood that such covers when provided are conveniently hinged to the

back element substantially along the lines 54 and 55.

While I have herein shown and described only certain embodiments of the features of my present invention, still I do not intend to limit myself thereto, except as I may do so in the claims to follow.

I claim:

1. A record album intended for standing support on a shelf or other substantially horizontal surface, said album including a back element and a rigid stud-supporting plate said plate extending from the back element substantially at right angles to one face of said back element, the back element extending to both sides of the so located stud-supporting plate, and record supporting stud projections carried by said rigid plate and projecting from the plate at both sides thereof, said projections at the two sides of the plate being substantially equal in amount to the extensions of the back element beyond the faces of the stud-supporting plate, whereby records may be simultaneously strung on the stud projections at both sides of the plate, substantially as described.

2. A record album as defined in claim 1, to-

gether with pedestal projections on the lower portion of the stud-supporting plate and projecting to both sides of said plate by amounts of projection substantially at least equal to the projections of the stud elements at the respective sides of the plate, to thereby provide base supports for the stud-supporting plate, substantially as described.

10 FOLGER ADAM.
